UNITED STATES PATENT OFFICE.

OLIVER B. YOUNG, OF DETROIT, MICHIGAN.

FORM FOR CONCRETE TRUSSES.

1,314,725.

Specification of Letters Patent.

Patented Sept. 2, 1919.

Application filed May 7, 1918. Serial No. 233,065.

To all whom it may concern:

Be it known that I, OLIVER B. YOUNG, a citizen of the United States, residing at Detroit, county of Wayne, State of Michigan, have invented a certain new and useful Improvement in Forms for Concrete Trusses, and declare the following to be a full, clear, and exact description of the same, such as will enable others skilled in the art to which it pertains to make and use the same, reference being had to the accompanying drawings, which form a part of this specification.

This invention relates to forms for concrete trusses, an object of which is to provide a form composed of several parts of the required character that may be assembled and positioned to receive the metal tension members and the concrete to form a complete truss. A further object of the invention is to provide forms of the general character stated that are adjustable to provide various lengths of cord members and diagonal or vertical web members. An additional object of the invention is to provide a form having a shape to make what I have hereinafter termed the joint between the cord and various web members centering thereon with the various parts of the form adjustable as to radial relation whereby the joint is adapted for use with trusses of various distances between cord members and of various lengths of spans. More particularly the object of the invention is to provide forms for what I have termed the joints of concrete trusses so constructed as to be adjusted to cover a wide range of sizes and design of truss and provided with portions adapted to connect the several joint members to provide forms for the cords and the diagonal and vertical web members. These several objects and the novel features of the invention are hereinafter more fully described and claimed and shown in the accompanying drawings in which—

Figure 1 is a plan view of the forms utilized in the making of a joint of a concrete truss.

Fig. 2 is a side view thereof.

Fig. 3 is a plan view of a joint of different type from that shown in Fig. 1.

Fig. 4 is a plan view of a joint of another type.

Fig. 5 is a section taken on line B—B of Fig. 1.

Fig. 6 is a similar section showing another type of construction.

Fig. 7 is a cross section of one of the arms of the form taken on line a—a of Fig. 1.

Fig. 8 is a plan view of a member used for connecting an arm of one joint with an arm of another joint.

Fig. 9 is a cross section taken on line D—D of Fig. 8.

Fig. 10 is a cross section taken on line E—E of Fig. 16 showing the connecting member in position on an arm of the joint.

Fig. 11 shows a form in cross section provided with a hinged cover.

Figs. 12 and 13 show cross sections of the other shapes of forms.

Fig. 14 is a cross section taken on line C—C of Fig. 3.

Fig. 15 is a cross section taken on line F—F of Fig. 4.

Fig. 16 is a plan view of forms for the two end panels and the center panel of a five-paneled "Pratt" truss.

Fig. 17 is a plan view of forms as assembled for the making of two end panels and center panel of a five-paneled "Howe" truss in which some of the members are formed of reinforced concrete and some of the members of steel bars or rods.

As is shown more fully hereinafter the forms herein disclosed may be assembled and a complete truss of reinforced concrete made and subsequently erected, or the forms may be assembled in the place to be occupied by the truss and subsequent to the curing of the concrete poured therein, the forms may be removed therefrom leaving the truss erected. In small work, however,

it is generally preferable to form the truss and then erect the same. A form for making a joint of a truss of the former character is shown in Fig. 1 and this form consists of several radial arms 1, 2, 3, 4 and 5 in this particular type of joint. These arms vary somewhat in shape as may be understood from the drawing and are connected together by a bolt 6 forming a pivot on which these arms may turn. The arms are preferably trough shaped in cross section as indicated in Fig. 7, or they may be of other shape as indicated in Figs. 11, 12 and 13 depending

upon the desired cross section of the concrete member to be formed therein. As will be readily understood, the form in section of concrete member may be of any desired type, 5 the arms of the joints and the connecting members therefor being of a shape to produce the required cross section of concrete.

In the type of joint shown in Fig. 1 the members 1 and 2 are adapted to form part of 10 one of the cord members of a truss while the parts 3, 4 and 5 form a part of the perpendicular and diagonal web members extending between the upper and lower cord members. This will be readily understood from 15 examination of Fig. 16 where the joint of Fig. 1 is shown at A. These radial members of a joint as shown in Fig. 1 have the pivotal ends thereof shaped to form a semi-circular basin from which the several cord 20 and web members extend and to form the basin each radial arm of the joint terminates in a comparatively flat portion 8 overlapped by the similar flat portion 9 for instance of another member, and these several 25 flat portions of the radial members form a bottom on which the concrete may be placed. The radial arms are further provided with the flange members 10 and 10, etc., that also overlap as is shown in cross 30 section in Fig. 5 forming a receptacle of a depth equal to or greater than that of the radial arms providing a retainer for the concrete. It is further noted that these several arms being pivotedly connected at 35 6 allow the arms to be changed in relative angular relation. Thus the form for a joint is adapted for the formation of forms for trusses in which distances vary between the upper and lower cord members or distances 40 vary between the vertical web members of the different joints or both. This will be understood for instance in Fig. 16 in which the horizontal cord members 12 and 13 are a certain distance apart and the diagonal 45 member 14 occupies a certain angle with the joints A and B. If these joint forms are to be used for the formation of a truss having a greater distance between the cord members 12 and 13, and with the same dis- 50 tance between the vertical web members 15 and 16, the angle between the diagonal members 14 and 16 and 14 and 12 will alter and this is accomplished by reason of the pivotal relation of the arms of the joint members. 55 It is further to be noted that the edges of the trough shaped portions of the radial arms shown at 17 are rolled to form a stiff edge and prevent bending or distortion of the edge in use.

60 The joint members may be of various types as is required in the construction of trusses of various types. For instance, the joint shown in Fig. 3 is indicated in use in Fig. 16 at C, and the type of joint shown 65 in Fig. 4 is indicated in use at D in Fig. 17

and another character of joint is shown at B and at E in Fig. 16. In each of the forms or molds for the joints of the truss, the members thereof are in pivotal relation to enable the angles of the radial arms to be 70 varied to suit either the character of truss or adjusted to the required angles. This pivotal relationship of the arms of a joint form may be secured in various ways. For instance instead of utilizing a central bolt 75 as shown in Fig. 5, the semi-circular flanges of the several arms may be turned one over another as indicated in Fig. 6. The rolled edges allow the arms to turn to assume various angles.

Two types of truss are shown in Figs. 16 and 17 respectively and any type of truss requiring cord and web members may be formed with the molds here described or variations thereof within the spirit of the 80 invention, and several types of joints are here shown for the purpose of illustrating the adaptability of the invention to fulfill the various requirements. For instance, the joint shown at C in Fig. 16 may be formed 85 by the device shown in detail more clearly in Fig. 3. It is to be noted that this device has two diametrically oppositely disposed legs 30 and 31 which are attached to the same plate 32 and these legs are provided 90 with the semi-circular flanges 33 connecting with the side members of each arm, and the flanges are spaced apart opposite the other arms 34 and 35 and the flanges 33 are en- 95 gaged by the flanges 36 of the legs 34 and 35 100 respectively so that at the center a substantially circular receptacle is formed from which extend the members 30, 31, 34 and 35. The plates of the two sets of arms are pivot- 105 ally connected preferably by the bolt 37 and the angular relationship may be varied from that of a right angle as indicated to angles of other degrees. Likewise in Fig. 4 a type of joint is shown as is used at D in Fig. 17 which is provided with arms extending at 110 a right angle one to the other, and this angle may be varied by reason of the pivotal relation of the two arms on the bolt 40. The two channel arms terminate in a plate 41 and 42 respectively overlapping as indicated 115 and having the overlapping side flanges 43. In the type of joint shown in Fig. 1 and Fig. 4 there is a space 44 between the adja- 120 cent ends in the outer side flanges of the arms allowing the arms to be turned back- 125 ward to a certain extent on the pivot. In case the arms occupy the position shown in the drawing when built into truss form shown for instance in Figs. 16 and 17, this space may be closed in any suitable manner as by a metal plate placed therein to prevent the semi-fluid concrete filling to flow there- through.

The connecting members 7 utilized be- 130 tween the radial arms of the joints, shown in

detail in Figs. 8 and 9, has the curved side members 46 which engage over the rim 17 of the radial arms as is shown particularly in Fig. 10, preferably in telescopic relation with the flanges of the arms, although such telescopic construction is not absolutely necessary. In order to change the length of forms for truss members the connecting members 7 may be made of various lengths and may also be positioned to overlap the joint members to a greater or less extent. If the forms used are of the open type shown in Figs. 1, 3 and 4 they are built up in the specific relation required by the proposed truss on a flat platform or surface preferably as nearly level as is possible, the joints being positioned the required distance apart and the arms of the joints connected by the members shown in detail in Fig. 8 and as indicated at 12, 13, 14 and 15 in Fig. 16. After the members have been assembled in the required relation as shown in said Fig. 16, the reinforcing metal is placed in position in the forms in the required relationship and the concrete then poured. With the open type of form used the face of the mold may be struck off by a wooden or metal plate so that the surface is substantially uniform in character and the concrete is allowed to harden in the forms. After hardening the forms are removed and the completed truss may be set in place by proper tackle for handling the same such as is used for handling steel and wooden truss members in present building and bridge construction. In the event that it is desired to cast a truss in place all the molds should be provided with a cover of some character such as is indicated in Fig. 11 preferably in hinged relation. That is, each arm of the joint should be provided with a hinged cover and each member 7 would be likewise provided with a similar cover and the forms erected and supported in place. By having the members covered as shown the concrete may be poured while the forms are in place and subsequent to the curing thereof the forms may be removed and thus the truss built in final position. Various types of trusses may be made as is suggested in Figs. 16 and 17. In Fig. 17, for instance, the vertical web members and upper cord are the only concrete members of the truss, the other members as *s*, *t*, *u* and *v* being formed by metal rods or bars and for use with such bars the flanges of the joint members, for instance as indicated in Fig. 15, should be provided with a slot or notch 50 through which the metal rod may extend as indicated at joint D in Fig. 17 and be embedded in the concrete at the joint and connected with the reinforcing members of the concrete portion of the truss as may be desired. The notch 50 in the flange of one leg of the joint registers

with the similar notch in the adjacent overlapping flange of the other leg and thus the several joints may have inserted therein the tension rods or bars as is shown. For this purpose the vertical connecting members 70 of the truss shown in Fig. 17 correspond in all general respects to the connecting member 7 shown in detail in Fig. 8 except that the lower end thereof is closed as indicated at 71 and is provided with slots 72 to receive the rods passing through the ends of these vertical web members. The slots or notches facilitate the insertion of the rods in the forms when used to make a truss having metal tension members lying outside of the concrete members. The forms have the side flanges positioned at a slight angle to each other to facilitate removal from the finished structure.

While I have described the forms as being particularly of use in the making of concrete trusses, it is evident that the forms may be used for other concrete structures as, for instance, in concrete boat construction in which vertical or horizontal rib members are connected with diagonal rib members after the general form of a truss, and such rib members are also found in concrete building construction. In fact the forms may be used wherever structures similar to that of a truss is to be made.

Two methods of using these forms in the construction of concrete trusses may be followed: First, the forms may be assembled on a platform in another position and location than that which the truss is intended to occupy in the completed structure. After the concrete has set and the forms are removed from same the truss may be carried to and erected in its permanent location. This is known as precast construction and is especially adapted to trusses of short spans such as 20 or 25 ft. The accompanying drawings are made with this idea in mind. Thus assembled forms for trusses are shown in plan view with top of form open to receive concrete and except in Fig. 11 this top of form is not inclosed and concrete may be struck level with a board or straight edge.

The second method of using these forms in the construction of a concrete truss is the placing of forms so that when truss is poured same will occupy its permanent position and when concrete has set the forms will be removed from same and truss will remain in its permanent location. While the drawings are made to show forms for precast concrete, trusses as mentioned above they are also intended for use in connection with concrete trusses poured in place. In this case a retainer will be needed on the face of the form shown as open in the drawings, to retain the fluid concrete when poured. A suggestion to meet this condition is shown in Fig. 11 whereby a lid or cover

is shown attached to the form by a hinge. Said cover may be made in several sections to each portion of form to which it is attached so that the concrete may be poured into the truss by stages and covers closed as forms are filled with concrete. From the foregoing description it is evident that by making the form of metal of several pivoted parts for the joints and the connecting parts 7 extending between the arms of the several joints as indicated, a truss of a great variety of sizes may be made with the same forms where the same cross section of cord or web member is possible, and that by the 10 use of forms of the character described the truss may be made and then erected subsequent to the manufacture thereof, may be made in the position to be permanently occupied thereby, and further by reason of the adjustability of the joints and of the 15 connection members, which may be made of various lengths, as may be required that the said forms may be used many times for the manufacture of trusses of various sizes and 20 thus are comparatively inexpensive by reason of the comparatively long life of the forms, and that the forms are much more quickly assembled for the formation of a truss than is possible with the usual wooden 25 forms.

30 What I claim is:

1. A form for making the joint of a concrete truss or the like consisting of a plurality of radially positioned members having 35 a shape in cross section to produce the desired cross section of concrete, the said members being adjustable about a center and having overlapping sides or flanges near the inner ends adapted to form a central concrete mass co-extensive with that formed by 40 the members.

2. A form for making the joint of a concrete truss or the like consisting of a plurality of members having a shape in cross 45 section adapted to produce the desired cross section of concrete to be poured therein, the members being in radial relation and pivoted together at the inner ends to allow adjustment of the angle between the said members, the said members being shaped adjacent 50 the inner ends to provide a substantially semi-circular receptacle, formed by overlapping extensions of the bottom of the members, overlapping arcuate side flanges 55 coextensive with the side flanges of the body thereof.

3. A form for making the joint of a concrete truss or the like consisting of a plurality of trough like members pivotally connected in radial relation, the sides of the 60 said members being arcuate in form and overlapping near the inner ends.

4. Forms for the manufacture of a concrete truss consisting of a series of adjustable forms adapted to be positioned in the 65

relation required to form the various members of a truss, the said forms consisting of a series of forms for making the joints of the truss and a series of forms connecting the members of said joint forms, the joint 70 forms consisting of a series of members in radial relation adjustable about a center to allow variation in angle between the members, the number of which corresponds to the number of cord and web members of 75 the truss to be formed uniting at that point and the said connecting members being similar in shape to the body of said joint members to produce cord and web members of the desired cross section. 80

5. A form for making the joint of a concrete truss consisting of a series of radially positioned open trough like members so connected as to be adjustable to vary the angle between the several members, the side flanges 85 of each member terminating near the inner end in arcuate portions overlapping similar portions of contiguous members.

6. A series of forms for the manufacture 90 of a truss composed of concrete compression members and metal tension members, consisting of a series of forms for making the joints of concrete members, the joint forms having conduit like arms adjustable in radial relation, the side portions of the arms 95 terminating near the center in arcuate portions overlapping similar portions of the adjacent arm, the said arcuate portions being notched to receive the metal tension members, and extensions for the said arms 100 to form the concrete cord and web members, the said extensions also being notched to receive the metal tension members whereby the same may be embedded in the concrete 105 members.

7. Forms for the manufacture of concrete 110 trusses or the like consisting of a series of forms for making the joints, the said joint forms consisting of a number of radially positioned members adjustable to allow variation in the angle therebetween, the said members being trough like in form with side flanges, the said side flanges terminating in arcuate portions near the inner end in overlapping relation with arcuate portions of an adjacent member, and a series 115 of connecting members extending between and in telescopic relation with similar arms of different joint forms.

8. An adjustable form for the manufacture 120 of concrete trusses consisting of a series of joint forms having a shape in cross section corresponding to the shape of concrete members to be formed thereby, the said members being in pivotal relation to allow 125 an adjustment of the angle between the several members of the form and being shaped at the inner ends to form a concrete mass at the junction of the members, the members of one joint being connected with the mem- 130

bers of another joint by a detachable member of a character to allow variation in the distance between the joints whereby cord or web members of various lengths may be made, the said several members of the forms being adapted to be assembled in relation to form the desired complete truss.

9. In a form for making a concrete truss, a plurality of radially positioned members shaped to receive plastic material and adjustable in angular relation.

10. Forms for casting a concrete truss consisting of a series of joint members having arms in radial relation and angularly adjustable, and a series of members for connecting the respective arms of the several

joints, the arms and the connecting members being of a character to receive and hold the plastic material substantially as described.

20

11. Forms for casting a concrete truss consisting of a series of joint members having arms in radial relation and angularly adjustable, and a series of connecting members in telescopic relation with the respective arms of the several joints to allow adjustment therebetween, the arms and the connecting members being of a character to receive and hold the plastic material substantially as described.
